NONSTOP BOX WRAPPING MACHINE

Ernest G. Rider, Philadelphia, Pa., assignor to
Stokes and Smith Company, Summerville, Pa.,
a corporation of Pennsylvania

Application May 8, 1940, Serial No. 333,995

4 Claims. (Cl. 93—54.2)

This invention relates to nonstop box wrapping machines.

The invention relates to a machine for automatically applying a wrap or wrapper comprised of a middle panel portion and end flaps or panels, to an open sided box, with the respective side and end flaps of the wrap adherent to the box side and end walls and turned over the respective upper edges of all walls to adherent termination on the inner upper surfaces of the box walls whereby the entire outer and upper surfaces of the box is covered by the adherent wrap or wrapper. Among other types of boxes utilizing such wrappers may be mentioned boxes for cigars. These initially have no resemblance to the cedar boxes conventionally used in the past art for cigar boxes, as they are made either of inferior wood or of cardboard or the like, so that the decorated and colored wrap suitably applied makes a more decorative and attractive package simulating the appearance of the expensive cedar boxes. Obviously there are many other types of boxes which are improved or completed by the addition of a suitable wrap.

As the art of wrapping boxes has developed hitherto, as represented for instance by certain machines of the Stokes and Smith type, the wrapper has been pasted, the box centered thereon and either directly or ultimately placed upon or pushed against a compressible spring-pressed plunger head, platform or lower forming block, with a two-piece or upper and middle or intermediate forming or pressure block placed in the box and arranged for vertical reciprocation under power. The vertically reciprocable forming or pressure block assembly is formed of the upper and middle blocks cam-actuated to progressively push the box and the partially adherent wrap downwardly with and on the plunger platform or head as the side flaps or panels of the wrapper are first moved up into contact with the side walls of the boxes by machine side rollers or the like, pursuant to which the assembly stops to permit horizontally slide reciprocating lap plates to be projected laterally of the box to turn the vertical edges of the side wall flaps or panels of the wrapper about the ends of the box, pursuant to which the assembly resumes its downward travel while the lap plates remain vertically fixed in engagement with the margins of the side flaps to hold the latter against the box ends with a wiping motion while the end flaps are applied to the ends of the box superposed over the turned in vertical edges, pursuant to which the upper flap edges of all of the side and end flaps are

turned over the upper edges of the box walls. The important thing in the consideration of this procedure in the light of the present invention is the stop hitherto necessary to permit the horizontally projected lap plates to function. This stop, at least after the machine has begun to wear, is accompanied by nerve-wracking sounds and shocks to adversely affect the efficiency of the operator, of itself it effects increased wear on the machine, ultimately results through wear and vibration in inferior and unstable work, and, of probably greatest importance, it slows down the machine and limits its output over that which is available without increased labor if the stop were eliminated.

It is among the objects of this invention to provide a wrapping machine having a nonstop run in a stop cycle of operation, for applying a wrap to a box; to provide improved linkage for actuating lap plates; to provide a new mechanical movement for lap plates and the like; to provide an oscillatable lap plate having a motion a resultant of two relatively normal motions; to provide a lap plate having a simultaneous outward and downward movement in synchronous relation to the downward movement of the box and wrap; to provide a movable lap plate so arranged that a wiping turning in operation can be secured for the full length of the turned in edge of the side flap of a wrap during a nonstop travel of the box and wrap past the effective support of the lap plate; to provide a nonstop box wrapping machine which automatically takes care of boxes of different depths without adjustment of the mechanism; to provide a nonstop wrapping machine which takes care of boxes of varying lengths or widths by a simple and facile adjustment; and many other objects and advantages will become more apparent as the description proceeds.

In the accompanying drawings forming part of this description:

Fig. 1 represents a fragmentary plan of a machine according to one exemplification of the invention, with the upper side flap wrapping rollers removed and an illustrative box in position therein, but with the wrapper omitted for clarity.

Fig. 2 represents a perspective of a box in operative centered relation to a pasted label showing the flaps and the assembly just before starting on the wrap-applying cycle of the machine (with the box thickness exaggerated for the type of wrap disclosed).

Fig. 2a represents a similar perspective of box

and wrap after the side flaps of the wrap have been adhesively applied to the box side walls.

Fig. 2b represents a similar perspective of the box and wrap after the edges or margins of the side flaps have been turned in to engagement with the end wall of the box.

Fig. 2c represents a similar perspective of the box and wrap of Fig. 2b after the end flaps of the wrap have been adhesively applied to such turned in edges and the end walls of the box.

Fig. 2d represents the box and wrap of Fig. 2c after the upper outer margins of the side and end flaps have been turned in over the upper edges of the walls of the box to adhesive attachment to the inner surfaces of the walls thereof.

Fig. 3 represents a side elevation of the improved lap plate of the invention, in one exemplification thereof, showing the auxiliary supporting link, and showing in successive dotted line positions the resultant progress of the advancing descending lap plate.

Fig. 4 represents a skeletonized side elevation of the machine according to a preferred embodiment, showing a fragment of the upper forming or pressure block in section in an illustrative box, also indicated in section, just before the upper forming block, lower plunger or forming block, plate or head, box and pasted wrap forming the assembly start to move together downwardly through the wrapper side-flap-applying-rolls with the side flaps extending substantially horizontally over the side-flap-applying-rolls, before the mechanism shown controlling the improved lap plates has been actuated to advance the lap plates.

Fig. 5 represents a horizontal section through the plunger shaft and a fragmentary plan of the cam lever and the lateral bosses on the plunger shaft to actuate the cam lever.

Figs. 6, 7 and 8 represent fragmentary side elevations of the lap-plate-actuating gear train and the assembly with the box and applied wrap showing the beginning and the completion of the concluding edge lapping movements of the box assembly through the machine after the initial position shown in Fig. 4, and respectively; the attachment of the side flaps to the box and the position of the parts substantially at the beginning of the movement of the lap plates of this invention; through lapping the edges of the side flaps about the end of the box in a non-stop sequence preliminary to the final application of the end flaps thereto and the turning in of all of the upper flap edges over the upper box edges.

It will be understood that in the broader implications of the invention it makes no particular difference what the nature of the box may be. That is it may be of metal, wood or cardboard or the like, or it may be combinations of these or other materials. It may be of any size or shape or proportions according to the capacity of the machine. It may be a plain oblong or square box, or it may be provided with a bottom flange or lateral extension of the bottom wall. The end walls may be of the same level as the side walls or higher or lower than same.

For illustrative purposes the box shown, for instance, in Fig. 2 may be considered to be formed of cardboard. The box comprises a bottom wall 10, end walls 11 and 12, and side walls 13 and 14. It will be assumed for illustrative purposes that the walls all terminate in upper edges 15 lying in a common plane. In order to indicate the fact that the walls have an actual

thickness it may be that the box shown in Fig. 2 may be considered to be exaggerated in thickness, in contrast to the wrap shown, as with such apparent wall thickness the perfect corners shown in the finished wrapped box of Fig. 2d may not be secured without providing either special slitting mechanism or the like, or a specific "knicked" type of wrapper (not shown herein). Obviously in the broader aspects of the invention this makes no difference as the box thickness may be anything desired, as may the characteristics or outline of the wrapper.

The wrapper comprises a central portion 16 (Figs. 4 and 6) preferably slightly tapered end flaps 17 and 18, (Fig. 2) and side flaps 20 and 21. Each side flap has side edge portions 22 which are ultimately to be folded about the end walls 11 and 12 of the box, as well as panel end edge portions 19 which are to be folded about the upper edges of the box and to adhesive engagement with the inner surfaces of the respective walls. Figs. 2, 2a, 2c and 2d illustrate diagrammatically the progression of the attachment of the wrap to the box.

Referring to Figs. 4 or 6 certain standard or conventional wrapping machine parts are shown which, standing alone, form no part of the present invention. Thus a cam driven vertically reciprocable plunger shaft 23 is provided, arranged for a substantially downward run or movement which is nonstop between the vertically spaced upper and lower limits of the run half cycle, in a stopped complete cycle of movement, in place of the conventional one stop in the half cycle of the present wrapping machines. The plunger shaft carries at its lower end the replaceable variably sized separable two piece forming or pressing block comprising upper block 24 and middle or intermediate block 25 as is conventional, and of such composite vertical extent as to be of approximately the same height as the box to be wrapped.

A table, platform, plunger head or lower forming block 27 is mounted on the upper end of a spring pressed plunger shaft 28. It is to be understood that the head 27 is preferably replaceable to accord with the lateral dimensions of the box to be wrapped (as is the pressure head or upper forming blocks), and that the head and shaft 28 are driven guidedly downwardly against the resilient resistance of a conventional compression spring, or the like, (not shown).

The machine is provided with upper wiper elements such as the rollers 30 and 31 disposed below the normal or initial starting positioning of the plunger head or lower forming block 27. These wiper elements are disposed in horizontal spaced parallel relation and arranged for adjustment in location to accord with changes in box size, and are respectively arranged to wipe the pasted or glued side flaps 20 and 21 of the wrap into adhesive contact with the side walls 13 and 14 of the box, as is conventional.

The machine is also provided with lower wiping elements such as journaled rollers 32 and 33, the axes of which are in a common horizontal plane in vertically spaced relation to a horizontal plane containing the axes of journaled rollers 30 and 31. Rollers 32 and 33 are similarly relatively adjustable and are used to apply the glued end flaps 17 and 18 adhesively to box end walls 11 and 12, as is conventional. It will be understood that any devices such as brushes and the like may be used in place of or supplementary

to any of the respective rollers 30, 31, 32 or 33. Referring to Fig. 4, the box is shown in fragmentary section with a fragment of the upper forming blocks 24 and 25 disposed therein and with the box resting upon the center panel 16 of the wrapper and with the latter resting upon the upper head or lower forming block 27 of the resiliently mounted compressible shaft member 28. When the assembly has been moved downwardly, toward the initiation of the wiping movements, to the position shown in Fig. 4, the side flaps 20 and 21 rest substantially upon or engage the rollers 30 and 31 preparatory to moving the flaps upwardly against the box walls. It will be obvious that downward movement of the assembly of upper and lower forming blocks, box and wrap, in moving from the position shown in Fig. 4 to that of Fig. 6, will have had the side flaps 20 and 21 rolled upwardly by rollers 30 and 31 into adhesive engagement with the respective side walls 13 and 14 of the box, as shown in Fig. 2a. The important part of the sequence of operative steps or at least of progressive positions of the parts, as no actual discontinuous downward motions are involved in the downward half cycle of the ring from the standpoint of this invention, is shown in Figs. 7 and 8 as securing the turning-in of the vertical marginal edges of the side flaps to the position shown in Fig. 2b. The mechanism for securing this functional result comprises the rotating lap plates, one of which is shown in a series of sequential positions in Fig. 3, so far as the actual wrap contacting element is concerned. The operating mechanism of the lap plate is shown in fragmentary form in Figs. 6 to 8 inclusive and in extenso in Fig. 4.

Oscillatably mounted upon suitable supports (not shown) and disposed in substantial parallelism with the axes of rollers 30 and 31 are the preferably squared shafts 34 and 35. As the shafts and their coupled mechanisms and appurtenances are substantially identical, but one will be described and similar reference characters will be used on the several parts of each.

It is contemplated that suitable means will be provided to cause adjustment of the shafts 34 and 35 relating to each other and to the forming blocks to accord with variations in sizes and proportions of boxes to be wrapped.

The lap plate 36 of this invention comprises the elongated wiping portion 37 having a lower toe 38 and a wiping surface 40 comprised preferably of spaced parallel semi-cylindrical elements 41 and 42 (Fig. 1) arranged to form the actual margin contacting portions of the lap plates. The lap plate 36 has a restricted rear neck 43 terminating in the spaced ear portions 44 and 45 suitably apertured to receive a pintle 46 and to engage between the ear portions 47 and 48 of a link 50. The surface 49 between lap plate ears 44 and 45, and recessed surface 54 between link ear portion 47 and 48 affords clearance in which spring element 51 is disposed embracingly about the hinge pintle 46, with its free ends bearing on the same side respectively of the link 50 and the lap plate 36, as at 52 and 53 to urge the lap plate resiliently in one direction. Preferably the ears 44 and 45 each have a protruding edge portion leading to a cut away or rounded edge portion with the protruding portions arranged to abut the link surface 54 to limit or stop the swinging motion of the lap 36 in the direction opposite to the spring resisted movement, so that it does not move out of substan-

tial alignment with the link 50, while the rounded edge permits lateral swinging against the resistance of the spring 51 in the other direction.

The link 50 at the front is pivoted at 55 to a second link 56 and the latter is pivoted at the lower end at 57 to a relatively fixed portion of the housing or frame journaling the squared shaft 34. The rear end of the lap link is pivoted at 58 to an arm 60 on the rotative element 61 having the square face 59 and mounted axially adjustable on but turning with the squared shaft 35. Obviously pivot 57 and element 61 are disposed in a guiding housing 69 and arranged for adjustments as units to accord with variable box lengths.

From an inspection of Fig. 3 it will be observed that rotation of the element 61, with the shaft upon which it is slidably mounted, from the full line position shown, will impart a compound motion to the lap plate through its supporting linkage, which is a resultant of differential outward and downward motions, in which the toe 38 is advanced laterally and downwardly leading the plate in its movement toward ultimate alignment with the vertical.

It will be evident that if the lateral and downward movements could be combined with the purely vertical motion of the assembly box and wrap in exact synchronized relation the vertical margins of the adherent side flaps of the wrap could be turned in about the ends of the box without "breaking the stride" of the advance, or in other words without stopping the cycle of assembly movement. By reference to Fig. 4 an illustrative mechanism for securing this result is disclosed. It will be understood that the resiliently held compressible shaft 28 constitutes the power factor for the lap plates.

As the downward descent of the supporting column 28 against the resistance of the spring associated therewith is as a function of the progress of the box and wrap through the machine, it will be observed that the synchronization of the shaft movement with the lap plate movement will secure the proper timed relation of the parts. To this end the spring pressed shaft 28 is provided with a pair of diametrically aligned studs 62 in operative aligned relation with the free end of the spring-pressed lap-plate actuating cam 63, pivoted at 64 to the bell crank lever 65 mounted on pivot 66 upon the base or frame element 67. The cam element 63 is pivoted in a clevis on the end of the bell crank and has an underlying extension 68 engaging under the arm 55 of the bell crank to positively limit the relative motion of the cam and lever in one direction and has a planar abutment 70 engaged by the lever carried spring 71 to resiliently permit limited relative movement of the cam and lever in the other direction to permit the studs 62 on their upward return trip with the power factor to wipe the rear surface of the cam 63 without actuating the parts in the return half cycle of the machine, as will be clear.

The cam 63 preferably comprises two spaced parallel cam elements 72, each having the cam surface 73 leading to the release passage 74, and one at least is provided with the cam guard 75 in spaced overlying relation so arranged that the impact of the studs 62 against the cam surfaces 73 cannot fail to result in a maintenance of the contact of the studs against the cam surfaces to insure controlled synchronous lap plate movement. It will be understood that a complete cycle of cam actuation takes place during the wiping

passage of the studs 62 against the surface 13, until the cam has been moved downwardly to such a position that the studs align with the release slots, 74, and the continued downward movement of the studs 62 through the release slots permits the cam and bell crank to return to its initial setting under the influence of the tension spring 76. The latter engages between an arm 71 of the lever, and the base 67, as will be clear. Upon the return stroke of the studs 62 the rear surface of the cam 13 is engaged and the cam is bent upwardly about its hinge point 64 against spring 71, to a degree sufficient to permit the free vertical passage of the studs to complete the return half cycle preparatory to the application of a new box and wrapper to the working parts and another cycle of wrap applying.

It being desired to secure variations in the strokes of the actuated parts, the arm 78 is 20 arcuately slotted as to 80 to receive the adjustably positioned pivotally element 81 to which the link 82 is pivoted. The other end of the link 82 connects through pivot 83 with rack 84. Obviously the length of the stroke of the rack depends upon the adjusted position of the element 81 in the slot 80, as will be clear. The free end of the arm 78 of the bell crank lever comprises a stop 85 abutting the adjustable abutment 86, to control the initial setting and degree of swinging of the cam and bell crank assembly.

It being understood that there is a complete cycle of reciprocation of the rack 84 for every down stroke of the assembly including power factor shaft 28, it will now be pointed out how this substantially horizontal reciprocation is made effective upon the lap plates of the invention.

Still referring to Fig. 4, it will be observed that the base frame 67 forms a journal for a shaft 35 carrying a pinion gear 86 in mesh with the rack 84 and keyed to the shaft so that at the front end the lever 87, keyed to the shaft 85, can actuate the vertical link 88 pivoted to the lever at 100. The link contains a transverse pivot 101, and at the upper end terminates in a pivot 102 connecting it with the vertical rack 103 slidably guided in the housing 104. The latter supports the rack gear 105 in mesh with the rack 103, and also journals the pinion gear 106 having the squared center opening and arranged to receive the transverse shaft 35 to drive same in an oscillatory cycle. From the previous description it will follow that the cyclic oscillation of either shaft 34 or 35 will cause the cyclic extension and retraction of both of the spaced respective lap plates operatively associated therewith.

It being understood that vertical shaft 28 is in one side of the center line of the assembly of box and wrap and actuating parts, so as to actuate a single shaft 35, although controlling both of the lap plates on said side, the rear end of the shaft 85 is coupled through a universal joint, (not shown), to drive the offset shaft 107, journalled on the frame 67, for synchronous actuation by the bell crank and cam assembly of Fig. 4. The free end of the shaft 107 carries a lever 108, driving a vertical shaft and rack combination 88, exactly similar to the first one described. The angle between the shafts 85 and 107 is such as to 70 permit actuation of shafts 34 and 35 on opposite sides of the box and wrap assembly.

Referring now to Fig. 6, it will be observed that the box and wrap assembly has passed downwardly through the side-flap-rollers 30 and 31, 75

so that the side flaps have become adherent to the box, and the vertical marginal portions still lie in the plane of the respective adherent portions as shown in Fig. 2a. At this point the studs 62 on the power factor have first contacted with the ends of the cam surfaces 13 and the linkage and train of mechanism has just started the inward and downward motion of the lap plates.

As shown in Fig. 7, the further continued downward motion of the assembly from the position of Fig. 6, finds the train of mechanism actuating the lap plates to a point where the advancing toes thereof have engaged the lowermost portion of the margins 22 and started to turn the margins in.

When the first contact of the oscillatable lap plates is made with the margins of the side flaps, as shown in Fig. 7, it is with the toes of the plates, which advancing first, strike the lower portion of the margins and turn them in so that instantaneously the margin is bent into a substantial triangle, as the upper edges have not been contacted. However, the continued downward movement of the assembly through the power factor continues the synchronous progress of the oscillatable lap plates and the heel or upper ends of the lap plates are projected forwardly after the toes have established the initial contact, and the advance of the lap plates is continued to a point at which the entire wiping surfaces or edges of the advancing lap plates have attained substantial verticality and the margins have been turned in to the four sided figures shown in Fig. 8.

It will be appreciated that the lap plates may be held against the turned-in margins for a small interval while the box assembly continues its descent. This enables the maintenance of the turned in engagement for a length of time sufficient to permit the end flaps 17 and 18 to be bent upwardly by the end flap rollers or brushes 32 and 33 to overlie or to be superposed upon the turned in vertical margins, as is common in this art.

The complete cycle of operation comprises a 45 wrapping half cycle in which the assembly starts at the top and passes all of the distance to the bottom of its stroke without a stop, during which, as noted the oscillatable lap plates are projected and moved downwardly to turn in the end margins. Before the assembly of box, wrapper and 50 forming blocks reach the bottom of their stroke it will be understood that the studs 62 on the power factor shaft 28 will have passed through the phase of contacting with the lateral cam surfaces of the arms 72, but will have proceeded further to the relief slots 75 which have by then been swung down into position for alignment with the descending power factor studs 62, during 55 which the lap plates will have been held stationary in their advanced depressed position to complete the vertical wiping on the turned in margin. The further descent of the studs of shaft 28 brings them clear of the relief slots 75, which relieves the cam lever of its distorted positioning and permits it to return to the normal or initial position under the influence of the spring on the base and bell crank. At the bottom of the downward half cycle of the machine, the upper edges 19 are turned in in the conventional manner by separating the upper and intermediate forming blocks while turn in fingers, not shown push the upper edges 19 across the upper wall surfaces 15, to subsequent brushing downwardly on the inside surfaces of the upper portions of the walls as is conventional, by lowering the upper forming block

into the box again from which it has withdrawn. This latter step as such forms no part of the instant invention.

After the wrap has been completely applied to the box at the conclusion of the non-stop downward half cycle, the entire assembly rises again to substantially the starting position, during the course of which the wrapped box is stripped from the forming blocks and ejected laterally, and again this is in accordance with conventional practices. This marks the return or upward half cycle of the complete run.

Note that the problem of synchronization of the descending assembly, with the lap plate movement, is secured by causing the descending assembly to constitute the power factor actuating the lap plates, although obviously if other synchronization and power means are desired, with the improved lap plates of this invention, they may be resorted to, without departing from the spirit and scope of the instant invention. For instance, it is contemplated that in place of the tension device 76 for returning the parts to the initial or starting position as shown in the drawings, such return may be accomplished positively in any desired manner as by a cam mechanism suitably disposed for the purpose and either independently actuated or coupled with the primary cam means for controlling the cyclic movement of the upper forming blocks. It is to be noted also that the lap plates with their slight flexibility of mounting are arranged for slight lateral bendings to accord with slight variations in the profiles of the boxes, and the like, while having a curved entering or leading edge to guide the lap plates past the ends of the box while in contact with the margins. It is pointed out as a further important feature of the invention with the lap plates as disclosed herein and with their actuation being controlled by the movement of the lower forming block, the initiation of the cyclic lap plate movement is predicated upon the arrival of the upper surface of the lower forming block substantially in alignment with the lower portion of the lap plate which is practically synonymous with the bottom surface of the box so that the lap plate cycle is always initiated in accordance with the location of the bottom of the box regardless of the vertical thickness of the box. This is important because it enables the machine with a single setting to take care of boxes with varying vertical heights.

It is contemplated both to build new machines incorporating the improved lap plate and its actuating means, or to provide the latter as attachments for existing machines.

I claim as my invention:

1. In box wrapping machines, a lap plate assembly comprising a lap plate having a turn-in portion, a link pivotally supporting the turn-in

portion at one end, means pivotally supporting the free end of the link, an oscillatable arm, pivot means engaging the turn-in portion with the said arm, and means for oscillating said arm whereby the turn-in portion is moved as a resultant of two angularly divergent motions.

2. In box wrapping machines, a lap plate assembly comprising a lap plate having a turn-in portion, a link pivotally supporting the turn-in portion at one end, means pivotally supporting the free end of the link, an oscillatable arm, pivot means engaging the turn-in portion with the said arm, means for oscillating said arm whereby the turn-in portion is moved as a resultant of two angularly divergent motions, and means for moving a box and wrap across the line of the turn-in portion movement in the direction of one of the motions of which the turn in movement is a resultant with the edge of the box in substantial alignment with the said turn-in portion.

3. In box wrapping machines, a lap plate assembly comprising a lap plate having a turn-in portion, a link pivotally supporting the turn-in portion at one end, means pivotally supporting the free end of the link, an oscillatable arm, pivot means for engaging the turn-in portion with the said arm, means for oscillating said arm whereby the turn-in portion is moved as a resultant of two angularly divergent motions, means for moving a box and wrap across the line of the turn-in portion movement in the direction of one of the motions of which the turn in movement is a resultant with the edge of the box in substantial alignment with the said turn-in portion, and means responsive to the movement of the box for actuating the said means for oscillating said arm.

4. In box wrapping machines, means operable with a box and associated wrap in a continuous movement between limits, a pivoted lever, a cam element mounted on the lever and comprising a curved surface communicating with a relief passage and arranged to be abutted by said first mentioned means to actuate the lever as a predetermined function of the movement of said first mentioned means, said relief passage being arranged to permit the continued movement of said first mentioned means while holding the lever in a predetermined immovable position, a lap plate, means mounting the lap plate for a resilient motion transversely and also in the line of movement of such box and wrap, and a train of mechanism coupling said lap plate as a function of the movement of such box and wrap and for maintaining the lap plate in a predetermined advanced position by the functioning of said relief passage during continued motion of the box and wrap.

ERNEST G. RIDER.
